UNITED STATES PATENT OFFICE

JOHN B. WELCH, OF NEW ORLEANS, LOUISIANA

DRYING APPARATUS

Application filed July 31, 1926. Serial No. 126,119.

This invention relates to a progressive dry kiln for drying lumber and other material.

One object of the invention is to provide a progressive dry kiln having a novel heating system which is adapted to permit the temperatures in different sections of the kiln to be controlled in a simple and efficient manner to maintain conditions within the kiln conducive to most favorable drying.

Another object of the invention is to provide a progressive dry kiln of novel and improved construction having a heating system by which it is rendered capable of use in drying both soft and hard woods.

A still further object is to provide a progressive dry kiln with a novel and improved heating system, comprising a series of heating units capable of maintaining a temperature range within the kiln which increases progressively and substantially uniformly from the green end to the dry end of the kiln, while maintaining efficient recirculation therein.

These and other features of the invention will be hereinafter described and particularly defined in the claims at the end of this specification.

In the drawings, illustrating the preferred form of the invention, Figures 1 and 2 comprise a vertical longitudinal section through the kiln; Fig. 3 is a vertical transverse section taken on the line 3—3 of Fig. 1; Figs. 4 and 5 comprise a horizontal section on the lines 4—4 of Fig. 1, and 5—5 of Fig. 2; and Figs. 6 and 7 comprise a similar view taken on the lines 6—6 of Fig. 1 and 7—7 of Fig. 2.

In the kiln drying of lumber, it has been found that in order to avoid surface drying and the cracking, warping, splitting, etc., incident to it, the initial heating of the green lumber should take place in air of sufficiently high humidity to accomplish this heating without appreciable evaporation of the moisture content of the lumber. Then, after the lumber has been thoroughly and uniformly heated in this manner, it is usually moved through the kiln, remaining in successive regions containing heated air of constantly diminishing humidity in order that the moisture may be gradually and uniform-

ly evaporated from within and throughout the lumber.

In practice, the above described drying process is conveniently carried out in a progressive dry kiln, such as is illustrated in the drawings, having an elongated heating chamber 10 with openings 12 and 14 at the opposite ends thereof closed by doors 16 and 18. The green lumber is stacked on trucks which are mounted on rails 20 and moved through the opening 12 into the green end of the heating chamber 10, and then moved progressively, step by step, through the heating chamber until they emerge from the dry end thereof through the opening 14.

In order that the air in the green end of the heating chamber may be maintained in a condition of relatively high humidity and that the lumber, in progressing through the kiln from the green end to the dry end, may encounter air of constantly diminishing humidity, it has been the practice to spray live steam into the heating chamber 10 from nozzles 22 located within the chamber.

In progressive dry kilns of the Welch type, illustrated in the U. S. Patent to J. B. Welch No. 1,517,928, of December 2, 1924, provision is made for circulating and recirculating the air within the kiln, and to this end, in the illustrated apparatus air ducts 24 and 26 are formed in the bottom of the heating chamber 10 throughout the length thereof. Fresh air is admitted to the ducts 24 and 26 through openings 28 and 30 formed therein, and is conducted through the ducts and discharged at the dry end of the kiln through openings 32, 34 therein.

The air ducts 24, 26, are also provided with by-pass openings 38, 40, near the green end of the kiln through which hot humid air is by-passed as set forth in detail in the above mentioned Welch Patent No. 1,517,928, to be carried along with the fresh air passing through the ducts and transferred to the dry end of the kiln. Recirculation is thus maintained and in the illustrated apparatus the ducts 24, 26 are provided with an additional set of by-pass openings 42, 44 located at a section of the kiln intermediate the dry and wet ends thereof. Recirculation through an ad-

ditional path is thus established from such intermediate section to the dry end of the kiln, assisting in the drying operation. Aspirators 45 are located in the ducts 24, 26 near the 5 by-pass openings 38, 40, and 42, 44, and serve to assist in maintaining the desired circulation.

Variations in temperature within the different parts of a progressive kiln have been 10 found to effect the rate of circulation and re-circulation of the air within the kiln, and also it has been found that temperature conditions suitable for hard wood kiln drying are not entirely suitable for the drying of soft 15 wood or very green wood.

For the efficient drying of hard woods, it has been found desirable to maintain a relatively large difference of temperature between the green end and the dry end of the 20 kiln, whereas in drying soft woods, and particularly green soft wood, a much higher green end temperature is required because of the excessive moisture content of such woods, and in order to provide a progressive kiln 25 suitable for drying both kinds of wood, and at the same time to maintain most efficient re-circulation, a novel heating system is provided.

Referring more particularly to the drawings for purposes of illustration, the heating system in the kiln may be regarded as divided into three sections, A, B and C, located in the dry end, the intermediate portion and the green end, respectively, of the kiln. As 30 shown in Figs. 4 and 5, the section A as composed, in the preferred form of four heating coils 46, 47, 48 and 49 located side by side beneath the rails 20; the section B comprises four heating coils 50, 51, 52 and 53; and the section C is composed of heating coils 54 and 55.

In order to accurately and definitely control the temperature conditions within the kiln, provision is made for controlling the temperatures in each of the sections A, B and C independently of the other sections. In addition, provision is made within the section A for controlling the temperature of the heating coils 46 and 49 independently of coils 47 and 48, and also for controlling the temperature of coils 47 and 48 independently of coils 46 and 49. Similarly, in section B, provision is made for controlling the temperature of the coils 50 and 53 independently of coils 51 and 52, and for controlling the temperature of coils 51 and 52 independently of coils 50 and 53.

To these ends the coils 50, 51, 52 and 53 of section A are provided with inlet headers 56, 57, 58 and 59 to which live steam is admitted through piping 60 from a supply pipe 61, a valve 62 being provided in the piping 61 to control the steam admitted to this section. In order to control the temperature in the coils 46 and 49, valves 63

and 64 are provided by means of which the supply of steam to the headers 56 and 59 may be regulated. Similarly, a valve 65 is provided by means of which the supply of steam to the headers 57 and 58 may be controlled to regulate the temperature of the coils 47 and 48.

In order to regulate the temperatures of the coils 50, 51, 52 and 53, which comprise the section B, in a similar manner, they are provided with inlet headers 66, 67, 68 and 69 to which live steam is admitted from the supply pipe 61 through a control valve 70 and piping 71. Valves 72 and 73 are provided to control the steam supply to headers 66 and 67 so that the temperature of coils 50 and 53 may be regulated independently and a valve 74 is also provided to control the steam supply to headers 67 and 68 and regulate the temperature of the coils 51 and 52.

The coils 54 and 55 comprising section C are provided with inlet headers 75 and 76 to which live steam may be admitted from the supply pipe 61 through a control valve 77 and piping 78 to regulate the temperature of these coils.

Each of the coils 46, 47, 48, 49, 50, 51, 52, 53, 54 and 55 is provided with an outlet header 88, from which the condensate discharges through a check valve 90.

In the drying of very green hard woods, it is sometimes desirable to have even less heat in the green end of the kiln than would be furnished by the afore-described system. In such cases it has been found that the supply of steam to the coils 54 and 55 may be shut off entirely and that a sufficient quantity of heat for the initial heating of the lumber in the green end of the kiln will circulate into the green end from the interior section of the kiln.

In the progressive kilns heretofore used, there have usually occurred abrupt changes in temperature between adjacent sections due to a much greater concentration of pipe in one section than in the other. In the present kiln this difficulty is overcome by arranging the heating coils so that the amount of pipe used increases gradually and substantially uniformly from the green end to the dry end. To this end, in the section C composed of coils 54 and 55, there are two layers of pipe (Fig. 1). In the next section B composed of coils 50, 51, 52 and 53, there are two layers in the left-hand portion and four layers in the right-hand portion, while in the section A comprising coils 46, 47, 48 and 49, there are four layers in the left-hand portion and six layers in the remainder (Fig. 2). In addition, to further aid in the gradual increase in the amount of pipe, there are a greater number of pipes in each layer of section B than in each layer of section C, and a greater number in

each layer of A than in a layer of section B.

In the above described arrangement of heating coils, the greatest concentration of piping occurs in a relatively small section at the extreme dry end of the kiln, thus offsetting the tendency of this end of the kiln to be cooled and rendering this end the hottest portion of the kiln. In addition, to aid in maintaining this high temperature at the dry end of the kiln, provision is made for heating any cold air which may leak into the dry end about the door 18. For this purpose a heating coil 92 is extended across the dry end of the kiln, beneath the rails 20, and between the end wall of the kiln and a baffle plate 94 also extending across the dry end of the kiln.

In the kiln drying of soft woods which contain a large percentage of moisture, it is necessary to apply considerable heat to the wood at the green end of the kiln to overcome the latent heat of vaporization of this moisture. In order, therefore, to provide additional heat when drying soft woods, an additional heating section D is provided which is used in addition to the sections A, B and C, and which comprises heating coils 96 and 98. These coils are of a length substantially equal to that of the coils 54 or 55 plus that of the left hand section of coils 50, 51, 52 or 53, and occupy a position parallel to and within the coils 54, 55, 50 and 53 and over the left hand portions of coils 51 and 52, as shown in Figs. 1 and 4. In order to admit live steam to the coils 96 and 98, they are provided with inlet headers 100 and 102 to which steam is admitted from the supply pipe 61 through a control valve 104 and piping 106. The coils 96 and 98 are also provided with separate outlet headers 110 from which the condensate drains through check valves 114.

As shown in Fig. 1, the portions of the coils 96 and 98 which occupy the green end of the kiln, have in the illustrated form, four layers of pipe, while the remaining portions which are in the intermediate section have two layers. This arrangement provides a convenient means whereby additional heat is furnished at the green end of the kiln to compensate for the heat absorbed in overcoming the latent heat of vaporization of the moisture in the wood, and also tends to offset the cooling effect exerted on this end of the kiln by the end wall and door.

The arrangement of the coils of the sections A, B, C and D is such and they are so positioned that, when they are used in the drying of soft woods, the temperature within the kiln increases substantially uniformly from the green end to the dry end. Also the coils are so arranged that they do not interfere with the circulation of air in the kiln. To this end, the coils 96 and 98 are spaced apart to allow the air free access in

the center of the kiln to the ducts 24 and 26 through the openings 38, 40, 42 and 44. In addition, the coils 50 and 52 are so positioned as to provide spaces between the coils and the side walls of the kiln through which the air has free access to the ducts through the outer portions of the openings 38 and 40.

While it is preferred to use the invention in the form disclosed, it will be readily understood that it may be embodied in other forms within the scope of the following claims.

Having thus described the invention, what is claimed is:—

1. In a progressive dry kiln, an elongated heating chamber, means for causing recirculation of the air within said chamber, means for progressively increasing the temperature within said chamber from the green end to the dry end thereof, and means for heating cold air which may leak into the dry end of said chamber before allowing it to mix with the heated air in said dry end of the chamber.

2. In a progressive dry kiln, an elongated heating chamber, means for causing recirculation of the air within said chamber, means for progressively increasing the temperature within said chamber from the green end to the dry end thereof, a baffle at the dry end of the chamber, and a heating coil between the baffle and end wall of the chamber for the purpose specified.

In testimony whereof I have signed my name to this specification.

JOHN B. WELCH.
